UNITED STATES PATENT OFFICE

JULIAN KENNEDY, OF PITTSBURGH, PENNSYLVANIA

ROLLING SHEETS

Application filed January 19, 1929. Serial No. 333,633.

This invention relates to the rolling of sheets and provides an improved process and apparatus whereby a high quality product may be produced with relatively low labor cost and upon a low capital investment.

In the ordinary method of rolling sheets a roller grasps a sheet bar with a pair of tongs and feeds it between the rolls of the mill. As it issues a "catcher" grasps it with another pair of tongs and lifts it over the top roll of the mill so that the roller can grasp it with his tongs to again feed it between the rolls. A roller boy operates the screw downs between passes. After the sheet bar has been subjected to a number of passes, say four, the partly formed sheets are paired and subjected to further rolling. This process is slow and a great deal of labor is involved. The task of catching the sheets and lifting them back over the top roll is exceedingly heavy work and is done under bad working conditions because of the heat which is radiated, not only from the material but also from the rolls themselves.

Various methods have been proposed for overcoming these difficulties. It has been attempted to place mills in a line and to automatically feed the material from one pass to the next. These projects have been failures. The material as it exists between passes is not of a character to be handled by fully automatic machinery. If the sheets are not properly squared as they enter a pass the product of the next rolling is not a rectangular sheet but is diamond shaped. There is always danger of a sheet edge turning up or down and these and many other conditions encountered in practical operation have made the proposed arrangements above described impractical. The so-called "strip-sheet" method which has recently come into use requires a very high capital investment and there are limitations on the thinness to which the material can be continuously rolled.

I provide for passing the material through successive stands, mechanically supporting the material between stands, the material being free of one stand before entering the succeeding stand, and guiding the material

into the stands by hand. Preferably means is provided whereby the workman may stand in substantial alinement with the line of travel of the material, and for this purpose I provide in the preferred form of my invention a platform overlying the table which supports the material between roll stands. This platform is preferably cooled and additional provision in the way of shields is made for protecting the workman from the heat.

Stops are preferably provided in the line of travel of the material so that its movement is checked before it enters a mill stand, and the workman has an opportunity to square it up. By reason of the fact that the workman is standing in the line of travel of the material, he is able to accurately guide it between the rolls with a minimum of effort. The sheet bars may weigh from fifty to ninety pounds, and obviously it is difficult if not impossible for a workman standing to the side of the line of travel of the material to properly guide it time after time.

After a desired number of reductions have been effected, the sheets are paired and the rolling is continued. Instead of the paired sheets being maintained in unchanging relationship throughout the rolling operation, as is ordinarily the case, I prefer that the workman shall so manipulate his tongs as to cause movement of one of the sheets on the other. When this is done between successive passes there is no danger of the sheets sticking together as frequently takes place in ordinary pack rolling. Because of the absence of stickers, a product having an improved surface, which is particularly valuable for automobile body sheets, is produced.

In the accompanying drawings illustrating the present preferred embodiment of my invention,

Figure 1 is a top plan view of a mill showing the mill stands arranged in a straight line;

Figure 2 is a side elevation;

Figure 3 is a top plan view to enlarged scale showing the platform, the supporting table and the stops in more detail, certain

parts being removed for the sake of clearness;

Figure 4 is a vertical longitudinal section taken on the line IV—IV of Figure 3, the 5 section being taken in such manner as to show the mechanism for actuating the stops from the workman's platform; and

Figure 5 is a detailed view showing the stop and its connections.

10 The present application covers broadly the method and apparatus as well as the specific form illustrated herein. Another form of apparatus is specifically described and claimed in my Patent No. 1,786,162, 15 dated Dec. 23, 1930.

The mill illustrated in the drawings comprises stands numbered 2 to 7 inclusive, each having its bottom roll driven through the usual connections by a motor 8. The top 20 rolls are undriven. Tables 9 extend between the stands, these tables being made up of side rails 10 carrying roller shafts 11. Ordinarily there will be no necessity for driving the roller shafts, particularly between the 25 stands where the sheets are still relatively short, as the material will issue from a stand with sufficient velocity to travel to a point where it can be grasped by the tongs of the workman. However, if it is desired, part 30 or all of the roller shafts may be driven. If any are driven they will ordinarily be the ones lying adjacent the exit side of a stand. In Figure 1 only a few of the roller shafts 11 are shown, the rest being omitted for 35 simplicity's sake.

A platform 12 on which a workman may stand lies over each table 9 adjacent the exit side of a mill stand. Each table comprises a water cooled base 13 supported on 40 legs 14 and having an upstanding back 15. The floor level is indicated by F in Figure 2 and it will be noted that the platforms are only a short distance thereabove so that a workman may readily step from the floor 45 onto his platform without danger.

As best shown in Figure 4, a heat shield in the form of an asbestos sheet 16 is placed on the back 15 to protect the workman from the heat of the rolls in the adjacent stand.

50 When the mill is in operation, he faces to the right as the mill is viewed in Figures 1, 2 and 3, and to the left as the mill is viewed in Figure 4. He is shielded from the heat of the rolls of the mills which he 55 faces by a shield 17 depending from a cross bar 18 extending between the housings. A horizontal shield 16a lies between the platform 12 and the rear table 9 and extends to the face of the rolls behind the platform.

60 As shown in Figure 4, this shield is supported immediately below the platform 12 and is re-inforced by metal strip. Its principal function is to conserve the heat of the rolled metal passing beneath it, and to prevent cooling thereof by the platform 12.

In operation a sheet bar is fed to the stand 2 of the mill. The sheet bars may be supported on a table 9*, if desired. After the sheet bar passes through the stand 2 it runs forward on the table 9 lying between the stands 2 and 3 and is there grasped by the tongs of a workman standing on the platform 12 and fed by him into the stand 3. The rolling continues through a desired number of stands, say through stands 2, 3, 4 and 5, and by this time the sheet bar has been sufficiently reduced in thickness to require pairing. The workman standing just beyond the mill stand 5 waits for two sheets to issue from the stand behind him, pairs 80 these and feeds them to the mill stand 6. The roller beyond the mill stand 6 "ruffles" the pair so as to eliminate any tendency to stick together, and then feeds the sheets to the stand 7. The operation may be continued through any desired number of stands.

By reason of the fact that the rollers are standing over the line of travel of the material as it is being rolled, they are able to 90 guide the sheets into the mills with a minimum of difficulty and with a maximum of accuracy. In practical operation there is sufficient variation in the sheets to require a certain amount of skill in handling, and the workmen are in the best possible position to apply their skill. All the difficulties of the automatic handling schemes heretofore proposed are therefore obviated.

In order to eliminate any danger of the material being fed into a stand without being guided by the roller, and to assist him in squaring up the sheets for rolling, stops 19 are provided adjacent the entering side of the different stands. These stops are carried on cross shafts 20, which shafts are arranged to be rotated by foot buttons 21 on the platforms 12. The connections are shown in detail in Figures 4 and 5. Each foot button 21 extends through a thimble 22 in the platform 12 and is connected to one arm of a bell crank 23. The other arm of the bell crank is connected to a link 24 terminating in a lever 25 on the shaft 20. A spring 27 normally tends to throw the stops 19 upwardly so that so long as the workman's foot is off the button 21 the material will not be fed into the rolls. After he has squared the sheets and has ruffled them or given them whatever further attention is necessary, he depresses the button 21 and shoves the sheet or sheets forward into the rolls.

From the foregoing it will be seen that instead of three men being required on a stand, only a roller is necessary. The investment cost is only slightly greater than in the case of an installation of ordinary hand mills and the capacity of the installation is high because there is no loss of time 130

as is the case where the material is passed back over the top roll in a hand mill, and the stands can all be operated at high speed. Ordinarily successive stands will be operated 5 at successively higher speeds to take care of the elongation of the sheet as it passes through the mill. The heavy labor required in ordinary sheet rolling practice is eliminated, and the working conditions are materially improved.

I have illustrated and described the present preferred embodiment of the invention. It will be understood, however, that it is not limited to the form shown as it may be otherwise embodied or practiced within the scope 15 of the following claims.

I claim:

1. In the method of rolling sheets, the 20 steps consisting in passing the material through successive roll stands, mechanically supporting the material between stands, the material being free of a stand before entering a succeeding stand, gripping the trailing end of the material with a hand tool, and 25 guiding the material into the stands by hand from a position in substantial alinement with the line of travel of the material into a stand.

2. In the method of rolling sheets, the 30 steps consisting in passing the material through successive roll stands, mechanically supporting the material between stands, the material being free of a stand before entering a succeeding stand, gripping the trailing 35 end of the material with a hand tool, and guiding the material into the stands by hand from a position in substantial alinement with the line of travel of the material into a stand and above the plane of such material.

40 3. In the method of rolling sheets, the steps consisting in passing the material through successive roll stands, mechanically supporting the material between stands, the material being free of a stand before entering 45 a succeeding stand, presenting a stop to the advancing material, squaring the material relative to the rolls in the next stand, and guiding the material into such stand by hand.

50 4. Apparatus for rolling sheets comprising a plurality of mills adapted to effect successive reductions, a table for supporting material passing from one mill to the next, and a workman's platform over the 55 table so placed that the workman may manipulate the sheets on the table from said platform.

5. Apparatus for rolling sheets comprising a plurality of mills adapted to effect 60 successive reductions, a table so placed that the workman may manipulate the sheets on the table from said platform, for supporting material passing from one mill to the next, a workman's platform over the table and 65 means for cooling the platform.

6. In a mill for rolling sheets a table for supporting material passing to a mill stand, and a workman's platform immediately above the table, the platform being so placed that the workman may manipulate the sheets on the table from said platform. 70

7. In a mill for rolling sheets a table for supporting material passing to a mill stand, a workman's platform immediately above the table so placed that the workman may manipulate the sheets on the table from said platform, and means for cooling the platform. 75

8. Apparatus for rolling sheets comprising a plurality of mills adapted to effect successive reductions, a table for supporting material passing from one mill to the next, a workman's platform over the table, a stop for checking the movement of the advancing sheets, and means for actuating the stop from said platform. 80

9. Apparatus for rolling sheets comprising a plurality of mills adapted to effect successive reductions, a table for supporting material passing from one mill to the next and extending therebetween, a workman's platform over such table and lying between the mills and so placed that the workman may manipulate the sheets on the table from said platform, and a shield for protecting a workman on the platform from the heat of the rolls in a mill stand. 90

10. Apparatus for rolling sheets comprising a plurality of mills adapted to effect successive reductions, a table for supporting material passing from one mill to the next and extending therebetween, a workman's platform over such table and lying between the mills and so placed that the workman may manipulate the sheets on the table from said platform, and a shield to the front and to the rear of the platform for protecting a workman on the platform from the heat of the rolls in the mills between which the platform is situated. 100

11. Apparatus for rolling sheets comprising a mill, a table for supporting material passing to or from said mill, a workman's platform over the table so placed that the workman may manipulate the sheets on the table from said platform, and a heat shield between the platform and the table. 115

12. Apparatus for rolling sheets comprising a plurality of mills in substantial alinement, tables extending between the mills for supporting material travelling from one mill to the next, and workmen's platforms over the tables each table being so placed that a workman thereon may manipulate the sheets on the table from such platform. 120

13. Apparatus for rolling sheets comprising a plurality of mills in substantial alinement, tables extending between the mills for supporting material travelling from one mill to the next, and workmen's platforms 125 130

over the tables each table being so placed that a workman thereon may manipulate the sheets on the table from such platform, the platforms being adjacent the exit sides of the mills.

5 14. Apparatus for rolling sheets comprising a plurality of mills adapted to effect successive reductions, a table for supporting material passing from one mill to the next, 10 a workman's platform over the table adjacent the exit side of the mill, a stop adjacent the entering side of the next mill, and means for operating the stop from the platform.

15 15. In the method of rolling sheets, the steps consisting in passing the material through successive roll stands, mechanically supporting the material between stands, the material being free of a stand before entering a succeeding stand, gripping the trailing ends of the sheets being rolled, and thus 20 guiding them into the stands by hand.

In testimony whereof I have hereunto set my hand.

25 JULIAN KENNEDY.
